(57) **CLAIM**

The ornamental design for a display screen with graphical user interface, as shown and described.

DESCRIPTION

The FIGURE is a front view of a display screen with graphical user interface showing my new design.

The outermost broken line rectangle showing an electronic device illustrates environmental structure and forms no part of the claimed design. The broken line showing of a display screen and all other broken lines showing portions of the graphical user interface illustrate portions of the article and form no part of the claimed design.

1 Claim, 1 Drawing Sheet
